United States Patent Office

Des. 191,473
Patented Oct. 3, 1961

191,473

SPECTACLE FRAME FRONT

Pearl F. Ashton, Providence, R.I., assignor to Rolyn Tool
& Finding Company, a corporation of Rhode Island

Filed Jan. 23, 1961, Ser. No. 63,647

Term of patent 3½ years

(Cl. D57—1)

FIG. 1

FIG. 2

FIG. 3

FIG. 4

FIG. 1 is a front elevational view of a spectacle frame front showing my new design;

FIG. 2 is an enlarged front elevational view of the trim on the left of FIG. 1;

FIG. 3 is a side elevational view thereof taken from the right edge of FIG. 2; and

FIG. 4 is a rear view thereof.

The dominant features of my design reside in the portions shown in full lines.

I claim:

The ornamental design for a spectacle frame front, substantially as shown and described.
